CLAIM

The ornamental design for a wheel for motor vehicle, as shown and described.

DESCRIPTION

FIG. 1 is a perspective view of a wheel for motor vehicle showing my new design;

FIG. 2 is a side view thereof; and,

FIG. 3 is a front view thereof.

The portions of the wheel for motor vehicle shown in broken lines are for illustrative and environmental purposes and form no part of the claimed design.

1 Claim, 3 Drawing Sheets
